UNITED STATES PATENT OFFICE.

GEORGE E. TITCOMB, OF NEW ROCHELLE, NEW YORK.

APPARATUS FOR FREIGHT TRANSFERENCE.

1,107,378.

Specification of Letters Patent. Patented Aug. 18, 1914.

Application filed April 2, 1912. Serial No. 687,981.

To all whom it may concern:

Be it known that I, GEORGE E. TITCOMB, a citizen of the United States, and resident of New Rochelle, in the county of Westchester and State of New York, have invented certain new and useful Improvements in Apparatus for Freight Transference, of which the following is a specification.

16 This invention relates to the removal and collection at shipping terminals of freight and merchandise from railroad cars or floating vessels, their distribution through or storage in suitable warehouses and the delivery from there or the aforementioned cars and vessels to other cars or other vessels, the entire invention forming, as it were, a straight line system of freight transference. In systems heretofore known for this same 20 general purpose, traveling trucks were used, running on overhead tracks and, of course, limited in their movement to the location of the tracks. Complicated power distributing arrangements and extensive switching devices were required in such cases. The 25 necessity of having numerous trucks travel unidirectionally over the same track, caused a standstill of all the trucks, whenever one truck was stopped for the purpose of loading or unloading.

The system forming the subject matter of the present invention is characterized by its great flexibility, inasmuch as an operating floor is provided, entirely separated from 35 the warehouse or storage floor or floors, and adapted for the free movement thereon of traveling trucks in every direction.

Among other objects of the invention is the provision of a storage or warehouse, 40 having one or more storage floors and an operating floor. A series of, usually closed hatchways is arranged on a so-called runway of the operating floor, and a series of continuous, normally open, hatchways, having channel rails or tracks contiguous thereto, is arranged on the remaining portion of the operating floor.

The floor under the runway of the operating floor, is provided with railroad tracks 45 for stalling freight cars. The floor or floors under the continuous hatchways, may be divided into storage compartments. The storage house is preferably located on or near a shipping pier, so that freight to and from cars or ships may be handled and distributed or stored in the building.

A traveling tower forms another feature of this invention and is distinguished by an overhanging platform or boom, onto which the traveling trucks are run. The tower itself is moved along the pierline on suitable tracks so that its boom coincides with the hatchways of a vessel, located alongside the pier. The truck on the overhanging boom drops the load, taken from a railroad car or a storage compartment, into the hatchway of the ship.

A system of overhead conductors is arranged for the purpose of distributing electrical energy over substantially any part of the operating floor, so as to move the trucks all over the floor and hoist or lower a load of merchandise wherever such trucks may be located.

A system of apparatus of the forementioned general description is peculiarly adapted for handling large amounts of merchandise and freight with greater economy in time and labor than in any analogous system heretofore in use.

The accompanying drawings illustrating the invention in one of its forms show in Figure 1, a side elevation and partly a section of a portion of a warehouse and a vessel adjacent thereto, comprising the main features of this invention. Fig. 2 is a plan view of the operating floor, at a reduced scale, on line A—A of Fig. 1. Fig. 3 is a detailed plan view of the traveling tower shown in Fig. 1. Figs. 4 and 5 are details of construction of the operating mechanism of the traveling tower. Fig. 6 is an enlarged detail showing the arrangement of the closed and open hatchways of the operating floor. Fig. 7 is a view on line B—B of Fig. 1, showing the arrangement of the conductors for the distribution of electrical energy. Fig. 8 are details of construction of the closed hatchways. Figs. 9 and 10 are a plan view and an elevation, respectively, of a traveling truck.

The general views, Figs. 1 and 2 of the drawing, illustrate a storage house located on the corner of a shipping pier and adapted to directly receive merchandise from or deliver to railroad cars or floating vessels.

The main storage floor is represented at 1, on which car platforms 2 are provided adjacent to car tracks 3 so that freight cars 4 may be stalled thereon and loaded and unloaded in the usual manner. The balance of the main floor 1, may be used for storage

purposes and divided by partitions 5 into storage compartments 6. The warehouse may also have more than one storage floor and these located at different levels, all however, accessible from the one operating floor, as hereinafter more fully described. A floating vessel, such as a steamer 7, barge, etc., is shown fastened to the pier and having a hatchway 8 for loading or unloading 10 its hold.

The operating floor 9 extends on one of the upper floors, throughout the entire building over the railroad tracks as well as over the storage compartments. The part of the 15 floor, located over the railroad tracks forms a runway 10, of preferably steel or reinforced concrete construction, having a series of normally closed hatchways 11 conveniently arranged over the car tracks 3 and the 20 car platform 2 and provided with hatchway covers 12 to close the hatchways.

The hatchway covers 12 are provided with annular rims 13 made of channel iron and resting upon brackets 14 of the floor construction 25 of the operating floor and are intended to be removed by means of the hoisting devices of the traveling trucks, as will be described farther below. In order to prevent accidents when the hatchways 11 are 30 kept open, guards 15 are inserted into the hatchways comprising rings made of channel iron resting upon the brackets 14 and extending above the level of the floor so that the wheels of the traveling trucks moving 35 on the operating floor are prevented from slipping off into the hatchways.

The portions of the operating floor, located above the storage floors show continuous hatchways 16 provided with channel 40 iron guards or rails 17, adjacent to the hatchways and substantially parallel to the longitudinal axes thereof. These rails prevent the truck wheels from sliding into the open hatchways. The hatchways over the storage 45 compartments may obviously be closed, by suitable covers, if so desired.

In the process of loading and unloading vessels, docked at the shipping pier, a traveling tower 18 is used, clearly shown in detail 50 and its relation to the warehouse and the vessel, in Figs. 1, 2 and 3.

A substantially vertical frame 19 extending suitably above the roof of the entire building, has rollers or wheels 20 to support 55 the frame 19 and permit its travel on convenient tracks 21 of the runway 10. A horizontal frame work 22, at right angles to frame 19, extends over the front portion of the storage house and carries a series of 60 rollers or wheels 23 at its rear end and adapted to travel on tracks 24 of the roof of the building. Suitable struts 25 connect the upper end of the frame 19 with the rear end of the frame 22 so as to form a rigid and 65 substantial structure on which a counter

weight 26 overcomes and balances any strain due to a heavy load in the overhanging boom.

The operating machinery of the traveling truck is indicated at 27 and comprises an electric motor and suitable translating devices, for either moving the entire tower along its tracks, or lifting or lowering the overhanging boom. 70

The machinery for moving the tower 18 is illustrated in Figs. 3, 4 and 5 and comprises 75 a primary motor 28 transmitting motion through a shaft 29 and convenient gears to a second shaft 30 and a set of bevel gears 31 then to a third shaft 32 and through a second set of bevel gears 33 to a vertical shaft 34. Another set of bevel gears 35, causes the 80 wheels 20, to travel on the track 21. A set of intermeshing gears 36 on the rear end of shaft 32, Fig. 5, cause a corresponding movement of the wheels 23 on the track 24 of the 85 roof.

A suitable clutch mechanism connects to or disconnects the entire operating mechanism from its primary motor, so that either the tower may be caused to travel along its 90 tracks, as forthwith will be described, or the overhanging boom may be raised so as to clear the rigging of a vessel docked at the pier. For this latter purpose a pair of cables 30' run from the hoisting drums 37 of 95 the power mechanism 27 over a roller 38 at the upper end of the beam 19 to a roller 39 at the outer end of the upper boom frame 40. This boom is pivoted to the main frame at its inner end and connecting rods 41, 42, 100 carry the lower boom frame 43 which is pivoted at its inner end in a similar manner as the upper boom. The entire boom, therefore, represents a parallelogram pivoted at the rear ends of the booms 40 and 43 and, 105 in its raised position, indicated in dotted lines, in Fig. 1 receiving additional security when overhanging by the toggled tie rods 44, 45.

The traveling truck 46 is shown in detail 110 in Figs. 9 and 10 and comprises a stationary platform 47 forming a rectangular central opening 48 in the bottom of the truck, through which, by means of a movable platform 49, loads may be raised or lowered. 115

The platform 47, by means of suitable bearings 50, rests upon the axles 51, having wheels 52, to run freely on the operating floor. To one of the shafts 51, rotation is imparted from a motor 53 through a suitable 120 transmission, such as gears or a chain, and the wheels on this shaft are swiveled, as shown at 54, and steered by a steering gear 55, controlled by the operator or driver of the truck. 125

The hoisting machinery comprises a primary motor 53, a transmission device 56 and the hoisting drums 57. The hoisting cable 58, running over cable rollers 59, 60, is secured to the movable platform 49, whereby 130

the latter may be raised and lowered through the opening 48 and the hatchways of the operating floor, to any part of the storage floor, or to the railroad cars stalled thereon or the hold of a vessel docked therat.

The principal feature of this automobile hoisting truck consists in lifting a load from any position below the platform of the truck 10 into the body of the truck and, after traveling any desired distance, depositing the same again at and to a point below the floor of the truck, without requiring more floor space of the operating floor than the actual size of 15 the truck.

Devices of a similar character, heretofore in use, required the employment of a swinging boom for lifting and lowering a load, occupying, therefore, considerable floor 20 space outside of the truck and causing frequent collisions between the traveling trucks, unless extreme care was used, to prevent the same.

A contact device or current collector 61 is 25 held against the electrical conductors 62 by the usual tension device and supplies electrical energy necessary for the operation of the motors on the truck.

The system of electrical conductors Fig. 7, 30 for the supply of current to the motors of the traveling trucks, comprises a set of substantially parallel overhead wires or bars 61, another similar set of the same 62 at right angles thereto and conductors 63 located 35 above the open hatchways 16 and conductors 64 for the overhanging booms of the traveling tower 18. The distance between the conductors is such that the current collectors of the traveling trucks are in contact with 40 the conductors in whatever position on the operating floor they may be and, thereby enabling the truck to travel in any desired direction on the floor.

What applicant regards as his invention 45 or discovery and desires to secure by Letters Patent of the United States is—

1. The combination with a building, of one or more storage floors, an operating floor, hatchways on said operating floor leading 50 to said storage floors, traveling trucks adapted to move loads on said operating floor and through said hatchways from and onto said storage floors, a power device on

each of said trucks, and means adapted to supply electric energy to said power devices 55 in any location on said operating floor.

2. The combination with one or more storage floors, of an operating floor located parallel to said storage floors, a series of hatchways on said operating floor and leading 60 to said storage floors, trucks freely traveling on said operating floor and adapted to move loads through said hatchways from and onto any part of said storage floors, a power device on each of said trucks, 65 and a series of stationary electrical conductors capable of supplying current to said power devices in any location on said operating floors.

3. The combination with a building, of 70 one or more storage floors, an operating floor, railroad tracks and storage compartments on said storage floor, hatchways on said operating floor giving access to said railroad tracks and storage compartments, 75 traveling trucks adapted to freely move loads on said operating floor and through said hatchways from and onto said railroad tracks and storage compartments, a power device on each of said trucks, and means 80 adapted to supply electric energy to said power devices in any location on said operating floor.

4. The combination with a building, of 85 one or more storage floors, an operating floor, hatchways on said operating floor leading to said storage floors, a traveling tower movable along said building, an overhanging boom on said tower, trucks adapted to travel on said operating floor and said boom 90 and to move loads thereon and through said hatchways from and onto said storage floors, a power device on each of said trucks, and means adapted to supply electric energy to 95 said power devices in any location on said operating floor and said boom.

In witness whereof the inventor has hereunto set his name in the presence of two subscribing witnesses, at New York, in the county of New York and State of New 100 York, this 25th day of March 1912.

GEORGE E. TITCOMB.

In presence of—

RALPH J. SACHERS,
GERTRUDE M. GRINDLAY.
